UNITED STATES PATENT OFFICE.

FRED DE CARDY, OF CHICAGO, ILLINOIS, ASSIGNOR TO WHITE BRASS CASTINGS CO., OF CHICAGO, ILLINOIS, A CORPORATION OF ILLINOIS.

TIMER.

Application filed August 1, 1924. Serial No. 729,449.

My invention relates to circuit making and breaking or spark distributing devices adapted for use in connection with the ignition circuits of internal combustion engines for distributing the spark to the cylinders thereof, and more particularly to a novel timer and timer-brush.

As is well known in the art, it has become the practice to distribute the ignition spark in internal combustion engines through a moving or rotating contact member or brush arranged for successive electrical contact with adjustable stationary contacts of a track in circuit with the spark producing means at the engine cylinder. While my present invention is especially directed to a novel spark distributing device or timer including a rotor having a brush for movement into successive electrical contact with the stationary contacts of the track or stator arranged within the casing or shell of the timer, as used in connection with internal combustion engines and especially as applied to automobiles, it is to be understood that the invention is adapted for other uses and in different relations.

It is an object of my invention to improve the functioning of devices of this sort, and with this in view the invention embodies and embraces a novel electrical contact between the movable contact making member or rotor and the stationary contacts or terminals; novel means for holding the movable contact member or brush in yielding relation or contact with the stationary contacts or terminals; to provide a device which will operate effectively, smoothly and continuously without the necessity of supplying oil thereto and which will not be harmed by the oil working in from the cam shaft of the timer, thus overcoming the objections previously caused by the presence of oil in the timer casing in timers as heretofore constructed.

The invention also has for its object the provision of a novel spark distributing device in which wear may occur without being detrimental to the making of contact between the contact surfaces; to provide a track having contacts so arranged that the brush is at all times in contact with metal and uneven wear of the track surface of the relatively stationary terminals or contacts owing to its composite structure of metal, such as copper, and insulating material,

such as fiber, prevented, and whereby a better ground for the rotor or movable contact making or brush member is obtained through the adjustable timer shell or casing constituting the stator, than is obtained through the timer or cam shaft; to provide a novel rotor having means for excluding and deflecting oil from along the timer shaft and the contact making surfaces of the timer so as to eliminate the objectionable results produced by the presence of oil within the timer casing; to provide a novel movable contact or brush and mounting or socket therefor grounded through the rotor to the timer or cam shaft and having simple and novel spring means for yieldably maintaining the brush in engagement with the stationary contacts of the track whereby a positive electrical connection is established at all times and uniformity of wear provided for.

It is also an object of the invention to provide a spark distributing device or timer which is simple and inexpensive, being constructed of a few simple parts which may be economically manufactured and readily assembled or dismantled for repair and replacement, in conjunction with the shell or casing structure having a detachable cap permitting convenient inspection of the working parts of the timer, as well as producing a timer having structural superiority and functional advantage over the spark distributing devices or timers of the prior art while also providing a spark distributing device adapted for use with various stationary terminal arrangements now on the market.

In order to acquaint those skilled in the art with the manner of constructing and employing my invention, I shall now describe, in connection with the accompanying drawings, a particular embodiment of the invention and the manner of its use.

In the drawings:—

Fig. 1 is a front elevation showing a timer of my invention and mounting thereof in connection with the spark distributing system of an automobile of well known make;

Fig. 2 is a transverse sectional view through a timer embodying my invention, taken substantially on the plane of the section line 2—2 of Fig. 3;

Fig. 3 is a longitudinal sectional view taken on the plane of the section line 3—3 of Fig. 2;

Fig. 4 is a fragmentary sectional view taken on the plane of the section line 4—4 of Fig. 2 and showing the mounting of the movable contact making member or brush 5 and means for yieldably holding the same in contact with the stationary contacts of the track or relatively stationary contact member; and

Fig. 5 is a fragmentary rear view of the 10 timer-brush or rotor.

Referring to the drawings in detail, in which like reference characters denote corresponding parts throughout the several views, 5 designates, generally, the commutator or 15 timer including an annular shell or casing 6 which is adapted to be received against the engine frame or wall 7 so as to be rotatably adjustable through the medium of an arm 8 within an annular boss or flange 9 of the 20 engine frame or wall 7, which latter may be the forward part of the crank case or other suitable part of the engine. The adjustment of the shell 6 is obtained by the connection of the spark rod 10 with the apertured arm 25 8, the latter having a forwardly offset sleeve for this purpose so as to obtain the necessary adjustment with relation to the cam or timer shaft 11, in order to advance or retard the spark in the usual manner. The timer is 30 here shown with a cylindrical casing or shell 6 provided with an annular seat forming recess 12 and a conically shaped end wall or cap 13 having its peripheral edge fitted in the seat 12 and held in place by a spring 14 secured by a bolt 15 or the like at one end and having its opposite or free end engaged in a depression 16 in the center of the cap. The spring exerts pressure against the cap and retains it in position, and in practice, a 35 certain relation is maintained between the center of the bolt 15 and the center of the hole in the arm 8 of the timer shell in assembling the parts and mounting the timer in position, which relation is adjustable to vary 40 the timing of the spark by rotatable adjustment of the shell as heretofore pointed out.

A ring 17 of insulating material, such as 50 fiber, is mounted in the shell 6 between spaced, parallel internal flanges or shoulders 55 18' and 19' formed or otherwise provided in the inner surface of the shell, which latter is preferably provided with a plurality, preferably four equi-spaced openings 18 through which insulating bushings 19, formed integral with the ring 17 or otherwise, project. The ring 17 is provided in its inner surface 60 with a series of equi-spaced segmental recesses 20 and 21, the former being located in line with the openings 18 and bushing 19 and the latter being located alternately or intermediately in equi-spaced relation with respect thereto, all extending across the width of the ring. Stationary terminals or contacts in the form of segments 22 and 23 are 65 mounted in the recesses 20 and 21 respective-

ly, the former having threaded stems 24 extending through openings in the ring and bushings 18, and extending outwardly of the peripheral or circumscribing wall of the shell to serve as binding or terminal posts to which the spark producing means, at the respective cylinders, are connected through suitable conductors (not shown). On the projecting stems 24 are threaded the usual binding nuts 25 or other suitable means between which the leads to the sparking devices or spark plugs are clamped. It is to be understood that the bushings 18 may be formed integral with the ring or separate therefrom, and it will also 80 be observed that they electrically separate or insulate the shell 6 from the stems and binding posts.

The metallic segments 22 and 23, which are preferably of copper or copper alloy, but which may be of other suitable current conducting material, are of arcuate formation to conform to the inner surface of the fiber insulating ring 17 and, as will be noted, form two series of contacts or terminals, the series 22 being preferably located 90 degrees apart for distributing the spark to the cylinders of a four-cylinder engine and having the threaded stems 24 and nuts or other threading means 25 forming terminal binding posts for the conductor wires, although it is to be understood that the arrangement and number of terminals or contacts will vary with the number of cylinders. The other series 90 of contacts are designated at 23 and these are also located 90 degrees for grounding the circuit between the contacts 22 to the shell 6 and the motor casting, as well as to produce a better ground, particularly on the movable or rotatable contact passing onto and off of the contacts 22, while also insuring constant engagement of the movable contact or brush with metal at the inner surface of the ring at all times to insure uniform wear and a smooth track surface whereby smooth 100 operation is made possible and interruptions in the circuit avoided. The alternate series of contacts 23 have stems 26 extending through radial openings in the ring 17 and connected to the shell 6 whereby the contacts 23 are grounded to the engine frame. While I have described a particular casing and stationary terminal arrangement which is preferred and possesses advantages over devices of the prior art as now used in the spark distributing systems of automobiles and the like, it is to be understood that the details of the casing and stationary terminal contact arrangement may be varied in connection 110 with the rotor and movable contact structure to be hereinafter more fully described.

The rotating contact or spark distributing member forming part of this invention, comprises a sleeve or hub portion 27 terminating at its inner end in or formed with an 120

annular flange or disc 28 slightly smaller in diameter than the internal diameter or opening of the insulating ring 17 and having its inner face adjacent the periphery beveled or flared outwardly toward the wall 7 as indicated at 29, so that any oil which finds its way along the shaft 11 and escapes between the shoulder formed thereon, as indicated at 30, and the adjacent end of the sleeve 27 10 projecting inwardly from the disc 28, will be checked and thrown outwardly by centrifugal action away from the contact making surfaces of the timer and ring 17 thereof.

At its outer end, the sleeve 27 which is mounted on the adjacent reduced end portion of the timer or cam shaft 11, as shown, is provided with a longitudinal countersunk slot 31 for the reception of the usual headed pin or set screw 32 which extends into the reduced end of the shaft 11 and fixes the sleeve 27 and disc 28 carried thereby for rotation with the shaft. A ferrule or flanged collar 33 is mounted over the outer end of the sleeve 27 to take up end thrust, and this collar or ferrule, together with the rotor or spark distributing member, is secured against displacement from the shaft 11 by means of the usual securing member or end nut and washer 34. It is to be understood that the commutator or timer shaft 11 is properly connected to be driven by the engine.

A socket 35 is carried by the disc 28 to extend radially from the sleeve 27, and is preferably stamped from sheet metal to provide a structure of channel or U-shaped cross section open at its ends and straddling the opposite shoulders of a thickened portion 36 formed on the disc 28 at its outer face, so as to cooperate with the disc to form a contact or brush carrying socket. This socket is suitably attached to the disc and as shown, is clipped thereto, being formed at its edges with ears 37 extended through spaced parallel slots 38 in the disc 28 and bent at right angles against the inner face thereof, as seen more particularly in Fig. 4 of the drawings. It will also be observed that the inner end of the socket is concave to conform to the sleeve 27 and the outer end is likewise arcuate, but cut on a convex curve to conform to the interior curvature of the ring and contacts carried by the latter. The disc 28 beneath the socket 35 is formed with a radial slot 39 and one or both sides of the socket are provided with longitudinal slots 40 which extend radially as does the socket and which are disposed in registry.

A movable contact or brush 41 is slidably mounted in the socket 35 for radial movement rectilinearly of the socket and has its inner and outer ends cut concavely and convexly as is the socket and for the same purpose. This brush is preferably, but not necessarily, of the gauze type and provided with a transverse opening 42 registering with

the slots 40. The contact or brush 41 is suitably grounded, being preferably slotted vertically of its inner end and having a ground wire 43 connected thereto, as indicated at 44. This ground wire or pig tail 70 is extended through the slot 39 and then through an opening or hole 45 in the disc at one side of the socket from the inner face of the disc and has its free end anchored around a binding screw 46 secured in a 75 threaded aperture in a thickened portion of the disc, which latter is preferably formed with a circular boss on one side for this purpose, as indicated at 47, on the inner side of the disc in Fig. 4.

As illustrated, the brush 41 is of non-circular or polygonal cross section to conform to the cross section or opening of the socket 35 for receiving the brush for free movement therein, so that the brush is held against turning movement in the socket and the ground wire or pig tail 43 permits the necessary movement of the brush, to ground the contacts 22 and engage the contacts 23 as the brush is moved into successive engagement therewith alternately. A shoulder or boss 48 is formed upon the outer face of the disc 28 substantially tangentially to the sleeve 27 and parallel with and slightly spaced from the inner end of the socket and brush, and a helical or coiled wire spring 49 secured on a screw or post 50 threaded in a hole in the disc or otherwise secured thereto to project at right angles in a sleeve 51, serves to hold the movable contact or brush 41 in yieldable relation with respect to the inner periphery or surface of the ring 17 and the stationary contacts 22 and 23 providing the track therein. As stated, the spring is mounted on the 105 sleeve 51 and retained in position by the head of the screw 50 while one arm of the spring extends through a slot 40 and into the opening 42 of the movable contact or brush 41 and terminates in a curved portion 110 or hook 52, the curvature being in the longitudinal dimension of the arm to provide a positive connection capable of resisting wear and prevent disengagement of the arm 115 from its operative connection with the relatively movable contact or brush. The other arm of the spring bears against the shoulder 48 to hold the spring under tension whereby the opposite arm will hold the brush in proper yieldable relation with respect to the insulating ring 17 and the contacts 22 and 23 seated therein. This spring gives the proper degree of tension to urge the brush into proper relation with respect to the terminals or contacts 22 and 23 and to insure positive contact without too much force such as would otherwise decrease the life of the timer, especially in devices heretofore provided and in which the exerting 120 force was too great in attempting to over-

125 130

come the objectionable results produced by the presence of oil in the timer. This construction permits the device to operate continuously and efficiently with a minimum of wear and without the necessity of supplying oil to the timer as has heretofore been customary. The device also eliminates the necessity of providing spring actuated rollers which require frequent oiling or other parts which are apt to get out of working order. Furthermore, the formation of the brush at its outer end will produce a wiping surface contact upon movement of the brush into successive engagement with the terminals or contacts 22 and 23, instead of a line contact such as that had with the contact making rollers of the prior art. Of course, it is understood that when the brush or relatively movable contact 41 engages the contacts 22 which are relatively stationary, but adjustable with the shell of the timer to advance or retard the spark, as is customary, that the circuit will be completed through the terminals or stems 24 and wires connected thereto, to distribute the spark in properly timed relation to the spark producing means or spark plugs of the engine cylinders. During this time, the circuit is grounded through the ground wire or pig tail 43, sleeve 27 and shaft 11 to the engine frame 7. However, the brush 41 is sufficiently wide to bridge the fiber gaps or portions between the contacts 22 and 23 at adjacent ends, and in this case, the circuit is completed through the contacts 22 and grounded through the contacts 23, stems or shanks 26 and shell 6 to the engine frame 7 in addition to the means heretofore described. When the brush is out of engagement with the contacts 22 it merely engages the contacts 23 forming grounds for the circuit so that the latter is broken. However, the brush is constantly engaging metal in the inner surface of the ring 17 and this provides for smoother running and uniform wear, especially in view of the fact that the brush bridges adjacent ends of the contacts 22 and 23 and more particularly seen in Fig. 2 of the drawings. It will be observed that the inner end of socket or housing 35 forming a guide means for the contact member or brush 41, which latter is preferably of wire gauze of copper and graphite to supply the necessary lubrication, is spaced from the hub or sleeve portion 27 so that when the brush moves inwardly, the inner end thereof extends tangentially to the hub 27 with openings or slots enlarging towards the sides between the hub and the inner end of the socket whereby any foreign matter or grease is forced out therethrough, as well as through the slots 39 and 40 during the movement of the brush member or contact 41, thereby preventing the socket from clogging up and in-

terfering with the free and unrestrained movements of the contact member or brush 41. In this manner, positive outward tension on the contact member or brush is insured so that the same will positively engage with the contacts of the casing or shell and ring therein, as well as free inward movement without friction or restraint due to foreign matter or grease clogging in the socket such as would occur where the same is closed at the inner end and on the sides, such as where the socket is formed integral with the sleeve or hub 27 and is therefore closed at its inner end.

While I have described my invention in connection with the details of a particular embodiment, I do not intend thereby to limit the invention to certain details, as I am aware and contemplate that modifications and changes may be made to adapt the invention for use under various conditions without departing from the essential aspects of the invention which are set out in the appended claims.

I claim:—

1. A timer including a sleeve, a disc projecting radially from the sleeve, a sheet metal socket clipped on the disc, a brush slideable in the socket and having an opening, and a wire spring mounted on the disc having one end anchored against movement by a lug formed on said disc and the other end extending into the opening of the brush to exert tension upon the brush.

2. A timer brush including a disc, a sleeve on the disc, a sheet metal socket having ears extended through slots in the disc and bent against one face of the latter to secure the socket in position, the socket having a slot therethrough, a brush slideable in the socket and having an opening adjacent the slot of the socket, a cylindrical boss on the disc, a coiled spring retained on the cylindrical boss and having one arm engaging a shoulder on the disc and the other arm engaging the opening in the brush through the slot of the socket to exert tension on the brush.

3. In a timer brush, a sleeve, a disc on the sleeve having a radial slot therein and slots at either side thereof, a socket of rectangular cross section having ears engaged through the last named slots and bent in contact with the face of the disc to retain the socket thereon, a brush movable axially only in the socket, a pig tail ground connection between the inner end of the brush and the disc and extending through the latter, and a two arm spring mounted on the disc and having one arm fixed thereon and the other engaging the brush to hold the latter under tension.

4. A timer including a sleeve, a disc projecting radially from the sleeve, a sheet metal socket on the disc and having slots in its

90

walls and its inner end spaced from the periphery of the sleeve, a brush slideable in the socket, a hollow cylindrical boss threaded internally from the face of the disc, a two arm coiled spring mounted on the boss and having one arm engaging a shoulder on the disc and its other arm extending through a slot in the socket and into an opening of the brush to exert outward tension on the latter, and a screw engaged in the threaded boss to retain the spring thereon.

5. A timer including a sleeve, a sheet met-

al socket having a slot, a spring having a helical portion and a pair of free ends, one 15 of said free ends being guided by the slot in said socket and the other free end being retained by a projection on said sleeve, said helical portion being pivotally mounted and positioned substantially centrally between said free ends to prevent the end of the spring in the slot from slipping out therefrom.

In witness whereof, I hereunto subscribe my name this 28 day of July, 1924.

FRED DE CARDY.
